UNITED STATES PATENT OFFICE.

JACOB RUDOLPH KAISERMAN, OF LIVINGSTON, MONTANA.

ATTACHMENT FOR ADDING MACHINES.

Application filed May 23, 1924. Serial No. 715,380.

This invention relates to adding machines, and has particular reference to a simple and efficient attachment thereto.

An object of the invention is to provide a simple, efficient and durable attachment which can be very readily applied to or removed from an adding machine and which when applied will effectively prevent the operation of the adding machine unless 10 certain designated parts are in the proper position.

Another object concerns the provision of an attachment which can be very readily applied to and removed from an adding 15 machine, and its attachment or removal will in only a very minor respect require an alteration of the construction and arrangement of the parts of most of the machines now in use.

20 A further object concerns the provision of an attachment so simple in its construction and operation that it can be applied to an adding machine with very little expenditure of time and labor and at a very 25 small cost.

The invention is illustrated in the drawings, of which—

Figure 1 is a simple diagrammatic side elevation of the parts involved, showing 30 them in a normal position;

Fig. 2 is a similar view showing the parts in an abnormal position; and

Fig. 3 is a perspective view of the attachment.

35 The form of the invention shown in the drawings is a preferred form, although it is understood that modifications in the construction and arrangement of the parts and in the character of the materials used may 40 be adopted without departing from the spirit of the invention as set forth in the appended claims.

More specifically the invention concerns the provision of a slidable bar or element 45 extending between a paper-carrying mechanism and the controlling key mechanism of an adding machine. This slidable bar is responsive to the movement of the paper-carrying mechanism from a normal to an 50 abnormal position, and a projection carried by the slidable bar is moved into the path of operative movement of the controlling key or bar when the paper-carrying mechanism is not in the normal position 55 so as to obstruct the operative movement of the controlling key mechanism and pre-

vent the operation of the machine until such time as the paper-carrying mechanism has been restored to a normal position.

More specifically still, the invention comprises a single bar slidably mounted on the frame of the machine and having one end bearing against a portion of the paper-carrying mechanism. This bar is constantly under the pull of a spring, tending to hold 60 it against the paper-carrying mechanism, so that as this mechanism is moved from the normal to an abnormal position the slidable bar will move from a normal to an abnormal position. The other end of this slidable 65 bar is disposed adjacent the operating or controlling key mechanism, and in the normal position of the slidable bar is not adapted to prevent the operative movement thereof, but in the abnormal position of the 70 slidable bar a projection or lip on the slidable bar is disposed in the path of operative movement of the controlling key mechanism so as to prevent a sufficient movement of 75 said controlling mechanism, whereby the operation of the machine is prevented.

The preferred embodiment of the invention shown in the drawings, which of course, is only one form in which the idea may be applied, shows a frame 1 of an adding machine in which is suitably mounted a carriage 2 adapted to support a sheet of paper 3. Against this paper a plate 4 bears. This paper-carrying mechanism is disposed rearwardly of a back plate 5 having an 80 aperture 6.

Through this aperture the end 7 of a slidable bar 8 extends. This bar at its other end 9 is U-shaped and embraces a stub shaft or other supporting projection 10 by which it 85 is supported and on which it is free to slide to a certain extent. Adjacent this end of the slidable bar there is disposed a controlling rod 11 the movement of which is controlled by a controlling key 12 and a spring 100 13 which in any suitable and well-known manner will pull the rod or bar 11 upwardly to perform certain operative functions, not necessary to describe. On this end of the slidable bar 8 there is disposed a stop 105 means in the form of a projection or lip 14 which, as shown at Fig. 1, is disposed out of the path of movement of any part of the controlling bar 11 but adapted, when moved to the position shown in Fig. 2, to be disposed in the path of movement of a portion 110 15 of said controlling bar 11 to prevent any

further upward movement of said bar 11 beyond the position shown in Fig. 2.

The end of the bar 8, adjacent the paper-carrying mechanism, is slotted, as shown at 5 16, and in this slot a screw or other pin 17 rides. The bar 8 is normally held against the paper-carrying mechanism by the pull of a spring 18 one end of which is fastened to the bar 8 and the other end of which is 10 fastened to the frame 1.

In the position of the parts shown in Fig. 1, which is supposed to be the normal position of the parts, the end 7 of the bar 8 bears against a portion of the paper-carrying mechanism. This portion is shown as 15 the plate 4. It is to be understood, however, that the bearing surface may be the paper carriage 2 itself, or the paper 3, or any other portion of this mechanism. Upon the de- 20 pression of the key 12, in a well-known manner, the mechanism is set into action by the initial depression of the bar 11, and then the upward movement of the same for the purpose of operating the adding machine and 25 making a proper record on the paper 3. However, the upward movement of the rod 11 beyond the position shown in Fig. 1 is 30 necessary to cause the operative movement of the machine. In the position shown in Fig. 1 the stop member or lip 14 is not in 35 position to prevent the upward movement, but if the paper-carrying mechanism moves from the normal position shown in Fig. 1 to an abnormal position, shown in Fig. 2, for one reason or another, the spring 18 will 40 pull the slidable bar 8 to the right and this movement will cause the interposition of the lip 14 in the path of movement of the controlling bar 11, so that the upward operative movement of this bar 11 is prevented and, therefore, the operation of the machine is impossible until the slidable bar 8 has been

moved back to normal. This can, of course, be done by the hand of the operator if he deliberately desires to effect this operation 45 with the paper-carrying mechanism in an abnormal position; but the normal intention is to maintain the slidable bar and its stop mechanism in the position shown in Fig. 2 until the paper-carrying mechanism has been 50 moved back to normal and by this movement has moved the slidable bar back to its normal position.

What I claim is:—

1. In an adding machine a paper carriage 55 having a normal position in which a printing action can take place and an abnormal position in which the printing action is to be prohibited, a controlling key having a path of operating movement, a single slidable bar extending between the carriage and the key, means for moving said bar in response to the movement of the carriage and means on said bar adapted to be disposed in the path of movement of the controlling key when the carriage has been moved out of its normal position.

2. In an adding machine a paper carriage, a controlling key mechanism, a single slidable plate extending between the carriage and the key, one end of said plate adapted to bear against a portion of the paper carriage, means for holding said plate against said carriage, said plate being movable in response to the movement of the paper carriage away from its normal position in which a printing action may take place and stop means carried by the slidable plate to be interposed in the path of operative movement of the key when the paper carriage is 75 out of normal position and when it is therefore desired to prohibit the printing action.

JACOB RUDOLPH KAISERMAN.
